UNITED STATES PATENT OFFICE.

CHARLES H. KIRBY, OF DETROIT, MICHIGAN, ASSIGNOR TO DETROIT LUBRICATOR COMPANY, OF DETROIT, MICHIGAN, A CORPORATION OF MICHIGAN.

CARBURETER.

1,387,275.

Specification of Letters Patent. Patented Aug. 9, 1921.

Application filed September 20, 1915. Serial No. 51,583.

To all whom it may concern:

Be it known that I, CHARLES H. KIRBY, a citizen of the United States of America, residing at Detroit, in the county of Wayne 5 and State of Michigan, have invented certain new and useful Improvements in Carbureters, of which the following is a specification, reference being had therein to the accompanying drawings.

10 The invention relates to carbureters of that type in which the admission of fuel to the mixing chamber is controlled by an automatic air valve. It is the object of the invention to provide means for supplying additional liquid fuel to said mixing chamber upon the sudden opening movement of said air valve, which might otherwise tend to impoverish the mixture due to the greater inertia of the liquid than that of the air. To 15 this end the invention comprises the construction as hereinafter set forth.

The drawing is a sectional elevation of a carbureter to which my improvements are applied.

20 A is the mixing chamber. B is the air inlet passage. C is an automatic valve in said air inlet passage having a central oil discharge nozzle D and a surrounding air passage E. F is a metering pin for restricting the oil passage to the nozzle, and which co-operates with said valve C to vary the restriction in different positions of the valve. G is the manually-operable throttle valve controlling the connection between the mixing chamber and the induction conduit to the engine. The construction is so organized 25 that when the valve C is closed the metering pin produces the maximum restriction to the supply of oil, while the air passing through the valve and the passage E surrounding the nozzle forms an ejector for discharging oil into said mixing chamber. When the suction is increased by the opening of the throttle G the valve C is lifted from its seat, which 30 results in increasing the flow of air, and by the relative movement of the valve and the metering pin also increasing the flow of oil to produce a proportionate mixture. If, however, the opening of the throttle is sudden 35 the inertia of the oil will retard its increase in flow, so that a greater proportion of air is admitted and the mixture becomes lean.

To overcome the defect just described, I have devised the following construction: H 40 is a piston connected to the valve C and

moving in a cylinder I, which forms in connection therewith a dash pot for retarding the opening movement of said valve, thereby retarding the flow of air. To increase the effectiveness of this dash-pot, a check valve 60 J is arranged in the oil supply, and closes upon the rise of the piston so as to prevent movement thereof excepting in so far as there is leakage of the oil around the piston. This closing of the check valve will cause a 65 rise in pressure on the oil, which I further utilize in raising a small quantity of oil above the normal level to form an auxiliary supply to the mixing chamber. Thus, as shown, K is a passage rising from the cylinder I, and L is a vent passage formed in the carbureter casing connected by a passage M leading to the mixing chamber, and also connected to the passage K. The arrangement is such that if the oil rises in the passage K above the vent L, the air drawn through said vent by the suction in the mixing chamber will cause the discharge of oil into the latter. Thus the effect of the sudden opening of the throttle is not only to 70 throw into action the dash-pot for retarding the movement of the valve C, but also to lift a quantity of oil into the path of the vented air passage, so that it is discharged into the mixing chamber to increase the richness of the mixture. On the other hand, when the abnormal pressure in the chamber I is relieved the level of the oil will drop below the vent L, which will permit air only to enter the mixing chamber, and the 75 restriction of the passage is such as to not materially effect the quality of the mixture by this additional air.

To permit the piston H to descend quickly when the valve C is closing a check valve N 80 is preferably arranged in said piston, said valve closing in the upward movement of the piston to produce a retarding and oil lifting effect, as has been described.

What I claim as my invention is:—

1. In a carbureter, the combination with a mixing chamber and an automatic valve controlling the air inlet thereto, of a dash-pot for retarding the opening movement of said valve, said dash pot having connection 105 with the oil supply, a check valve for closing the oil supply when said dash-pot is in action, an oil passage rising from said dash-pot filled by the pressure in said dash-pot 110 when said check valve is closed, and a vent

passage connecting with said mixing chamber intercepted by said oil passage.

2. In a carbureter, the combination with a mixing chamber, of an automatic valve controlling the air admission to said chamber, a cylinder connected with the oil supply, a piston in said cylinder connected to said automatic valve, a check valve in the oil supply, a passage leading upward from said cylinder above the normal oil level, and a vent passage connecting with said mixing chamber intercepted by said oil passage.
5. In a carbureter, the combination with a mixing chamber, of an automatic valve controlling the air admission to said chamber, a cylinder connected with the oil supply, a piston in said cylinder connected to said automatic valve, a check valve in the oil supply preventing back pressure acting upon the oil supply as the piston rises and a passage leading upward from said cylinder above the normal oil level and communicating with the mixing chamber.
10. In a carbureter, the combination with a mixing chamber, of an automatic valve controlling the air admission to said chamber, a cylinder connected with the oil supply, a piston in said cylinder connected to said automatic valve and forming a dash-pot therefor, a check valve in the oil supply closed by the rise in pressure in said cylinder due to the lifting of said valve and piston, a check valve permitting the free descent of said piston, a passage connecting with said cylinder rising to above the normal level of the oil, and a vent passage connecting with the mixing chamber intercepted by said oil passage.
15. In a carbureter, the combination with a mixing chamber, of an automatic valve controlling the air admission to said chamber, a cylinder connected with the oil supply, a piston in said cylinder connected to said automatic valve and co-acting with said cylinder to form a dash-pot for said valve, a check valve in the oil supply closed by the rise in pressure in said cylinder due to lifting of said valve and piston, a check valve permitting the free descent of said piston and a passage connecting with said cylinder rising to above the normal level of the oil and communicating with the mixing chamber.
20. In a carbureter, the combination with a mixing chamber and an automatic valve controlling the air inlet thereto, of a dash-pot for regarding the opening movement of said valve, said dash pot having connection with the oil supply, a check valve for closing the oil supply when said dash-pot is in action and an oil passage rising from said dash-pot filled by the pressure in said
25. In a carbureter, the combination with a mixing chamber, of an automatic valve controlling the air admission to said chamber, a cylinder connected with the oil supply, a piston in said cylinder connected to said automatic valve, a check valve in the oil supply preventing back pressure acting upon the oil supply as the piston rises and a passage leading upward from said cylinder above the normal oil level and communicating with the mixing chamber.
30. In a carbureter, the combination with a mixing chamber, of an automatic valve controlling the air admission to said chamber, a cylinder connected with the oil supply, a piston in said cylinder connected to said automatic valve and co-acting with said cylinder to form a dash-pot for said valve, a check valve in the oil supply closed by the rise in pressure in said cylinder due to lifting of said valve and piston, a check valve permitting the free descent of said piston and a passage connecting with said cylinder rising to above the normal level of the oil and communicating with the mixing chamber.
35. In a carbureter, the combination with a mixing chamber, of an automatic valve controlling the air admission to said chamber, a cylinder connected with the oil supply, a piston in said cylinder connected to said automatic valve, a check valve in the oil supply preventing back pressure acting upon the oil supply as the piston rises and a passage leading upward from said cylinder above the normal oil level and communicating with the mixing chamber.

dash-pot when said check valve is closed, said passage having communication with the mixing chamber.

5. In a carbureter, the combination with a mixing chamber, of an automatic valve controlling the air admission to said chamber, a cylinder connected with the oil supply, a piston in said cylinder connected to said automatic valve, a check valve in the oil supply preventing back pressure acting upon the oil supply as the piston rises and a passage leading upward from said cylinder above the normal oil level and communicating with the mixing chamber.

6. In a carbureter, the combination with a mixing chamber, of an automatic valve controlling the air admission to said chamber, a cylinder connected with the oil supply, a piston in said cylinder connected to said automatic valve and co-acting with said cylinder to form a dash-pot for said valve, a check valve in the oil supply closed by the rise in pressure in said cylinder due to lifting of said valve and piston, a check valve permitting the free descent of said piston and a passage connecting with said cylinder rising to above the normal level of the oil and communicating with the mixing chamber.

In testimony whereof I affix my signature in presence of two witnesses.

CHARLES H. KIRBY.
